DRYING APPARATUS

Fred S. Boltz, Mansfield, Mass.

Application March 25, 1938, Serial No. 198,048

8 Claims. (Cl. 34—82)

The present invention relates to apparatus for use, especially, in drying laundry by means of heated air.

It has been considered good practice from the view point of economy and efficiency to circulate air through a drying chamber and heating chamber a number of times before discharging the heated air. While this practice has been economical, it also possesses objectionable features. Thus, the heated air collects fine particles of lint from the dried clothes and an objectionable odor is imparted to the clothes from the heated lint. Attempts to remove the lint have been unsuccessful and have led to the less economical practice of discharging the heated air after it has once passed through the clothes being dried.

The present invention contemplates a drying apparatus in which the objectionable features of the former practice are eliminated while retaining the advantages due to recirculation of the air. An apparatus may be constructed in accordance with the invention to provide a compact arrangement in which the stream of air leaving the heating chamber, and before returning thereto, is divided and passed into and through a plurality of small drying compartments each containing a relatively small lot of clothes to be dried. In normal operation of such an apparatus each of the small lots of clothes usually is in a different stage of drying and, consequently, the drying is accelerated greatly due to the low drop in temperature of the heated air being circulated. If rotatable clothes receptacles are employed in the drying compartments, the operation of each may be controlled independently of the other for loading and unloading purposes. In such an apparatus the space occupied for a given drying capacity is reduced to a minimum.

The invention will be more clearly understood from the following description in conjunction with accompanying drawings: in which,

Fig. 1 is a front elevational view, partly in section, of an apparatus embodying the invention;

Fig. 2 is a sectional view taken upon the line 2—2 of Fig. 1;

Fig. 3 is a detail longitudinal sectional elevational view of a portion of the apparatus.

Figs. 4 and 5 are fragmentary detail sectional views of portions of the apparatus; and

Figs. 6, 7 and 8 are diagrammatic views illustrating the action which takes place during the operation of the apparatus.

Before explaining in detail the present invention

it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

An apparatus embodying the invention as illustrated in the accompanying drawings comprises a sheet metal casing having a front wall 10, a back wall 11, a top wall 12, side walls 13 and 14, and bottom 9. The bottom portion of the front wall is closed by doors D. A partition 15 extends vertically parallel to the front and rear walls 10 and 11 and spaced a short distance forward of the rear wall 11. The space between the front wall 10 and the partition 15 is divided by a horizontal partition 16. The partitions 15 and 16 divide the interior of the apparatus into a heating chamber 20, a hot air chamber 21 and a cool air chamber 22. The partition 16 has an opening 23 providing communication from the heating chamber 20 to the hot air chamber 21. The partition 15 is provided with a pair of horizontally spaced circular openings 25 positioned above a similar pair of openings 26 each providing communication between the hot air chamber 21 and the cool air chamber 22. The partition 15 also has a pair of openings 30 providing communication between the cool air chamber 22 and the heating chamber 20.

A heater H is positioned within the heating chamber 20 between the openings 30 and the opening 23 and includes a radiator R which may be supplied with steam. A stack 31 depends through the top wall 12 into the heating chamber 20 to near the bottom of the latter. A shaft 32 rotatably mounted in bearings in the front wall 10 and the partition 15 extends through the stack 31 and carries a flap damper 33 controlling the outlet from the heating chamber 20 through the stack 31. An operating handle 34 is suitably fixed upon the shaft 32 for adjusting the damper 33. A pair of shafts 35 extend through the rear wall 11 and are rotatably mounted in bearings 36 carried by brackets 37. A suction fan 38 is fixed upon each of the shafts 35 within the chamber 20 adjacent the openings 30. A pulley 40 is fixed upon each of the shafts 35 near its outer end and each is connected by a belt 41 with a

pulley 42 fixed upon the armature shaft of a motor 43 supported upon the top wall 12.

The front wall 10 is provided with pairs of openings 45 and 46 opposite the pairs of openings 25 and 26, respectively, in the partition 15. Annular plates 47 and 48 surround the openings 45 and 46 respectively and are secured to the front wall 10. The inner edges of the plates 47 and 48 are provided with inturned flanges 50 and 51. Two pairs of hollow sheet metal cylinders 60 and 61 extend between and are secured to the front wall 10 and the partition 15 with the open ends of the cylinders 60 are adjacent the openings 45 in the front wall 10 and the openings 25 in the partition 15 and with the open ends of the cylinders 61 adjacent the openings 26 and 46 in the partition 15 and front wall 10 respectively. The cylinders 60 and 61 are provided with openings 60' and 61' respectively in the region thereof most remote from the heating chamber 20 and providing communication with the hot air chamber 21.

A plurality of bearings 66 extend through the rear wall 11 at points opposite the openings 25 and 26 in the partition 15 and are supported by brackets 67 suitably fixed upon the rear wall 11. A shaft 68 is rotatably mounted in each of the bearings 66. A pulley 69 is loosely mounted upon each of the shafts 68 and each is connected with a pulley 70 by a single belt 71. A friction clutch C provides a driving connection between the pulley 69 and shaft 68. The pulley 70 forms part of a speed reduction mechanism G driven by a motor M which is carried by a bracket 12 fixed upon the rear wall 11. A spider 73 is fixed upon the inner end of each of the shafts 68 and each supports a perforated cylinder 75 extending into each of the cylinders 60 and 61 and providing a clothes receptacle. An annular flange 76 is fixed to the front end of the receptacle 75 and extends radially inward to leave an opening 77 opposite the openings 45 and 46 in the front wall 10. The members 76 are spaced from the front wall 10 to leave an annular passage 78 providing communication between the hot air chamber 21 and the interior of the receptacle 75. A perforated disk 79 is positioned across the back end of each perforated cylinder 75.

A brake mechanism is associated with each receptacle 75 to control its rotation irrespective of the others. Thus, an opening 80 is provided in the front wall 10 adjacent each of the openings 45 and 46 (Figs. 1 and 4). A brake shoe, such as a strip of metal 81, is secured at one end by rivets 82 to the inner surface of the front wall 11 adjacent the opening 80 so as to extend across the same adjacent the surface of the flange 76. A lever 83 is pivotally mounted upon a bracket 84 and is provided at its inner end with a cam surface 85 adapted to project through the opening 80 and engage the brake shoe 81.

The friction clutch C for connecting each pulley 69 to its shaft 68 (Fig. 5) comprises a collar 88 fixed upon the shaft 68 carrying a brake or clutch lining 89. The lining 89 is adapted to engage one end of the hub of the pulley 69. A sleeve 90 slidably mounted upon the shaft 68 is provided with a brake or clutch lining 91 adapted to engage the other end of the hub of the pulley 69. Each of a plurality of pins 92 carried by the collar 90 slidably engages a bearing 93 communicating with a cavity 96 formed in the cylindrical wall of a cup-shaped member 94 which is secured upon the outer end of the shaft 68 by a bolt 95. Each of the pins 92 is provided with an

enlarged head 97 positioned in the cavity 96. A spring 98 is interposed between the head 97 and the bottom of the cavity and tends to urge the sleeve 90 and the clutch lining 91 resiliently in engagement with the end of the hub of the pulley 69.

Hooks 100 and 101 fixed upon diametrically opposite points of each of the stationary cylinders 60 are adapted to receive hooks 102 and 103 fixed upon the upper edge of screens 104 and 105 respectively thereby permitting the screens to hang by gravity across the passage between the cylinders 60 and 61 and across the air passage between the cylinders 60 and 61. Spaced hooks 107 and 108 are also secured upon each of the cylinders 61 and are adapted to receive hooks 109 and 110 carried by the upper end of screens 111 and 112 respectively so that the latter may rest upon the bottom of the apparatus with their lower ends in engagement thus extending across the air passage below the cylinders 61.

A tank 115 is suitably supported upon the top wall 12 and is adapted to contain a deodorant. The tank 115 is connected by a pipe 116 to a faucet 117 positioned above a funnel 118 which communicates by a pipe 119 with an open pan 120 located within the hot air chamber 21. Perforated pipes 125 are positioned adjacent the inner surface of each of the screens 104, 105, 111 and 112 and are connected with a compressed gas supply pipe 126 through valves 127.

In the operation of the apparatus power is supplied from the motor 43 to the suction fans 38 which cause air to circulate through the cool air chamber 22, the heater H, thence through the passage 23 into the hot air chamber 21. The air stream divides in the chamber 21 and passes through openings 60' and 61' in the bottom of the chambers 60 and 61 and through the passages 78. After entering the chambers 60 and 61, the air passes through the receptacles 75 and back to the cool air passage 22. At the same time power is supplied from the motor M to each of the shafts 68 to rotate the receptacles 75 which contain the clothes to be dried. During the circulation of the air a certain proportion of the moisture containing the air is exhausted through the stack 31 and is replenished by fresh air drawn in through the openings 45 and 46.

When it is desired to load one of the receptacles 75 with a batch of clothes to be dried or to remove a batch of dry clothes therefrom, the lever 83 is actuated to cause the brake shoe 81 to be brought into engagement with the flange 76 thereby stopping the rotation of the receptacle 75. This is permitted by slippage between the pulley 69 and the clutch C. The clothes are inserted and removed through the openings 45 and 46 without opening or closing doors as is usually necessary. Inasmuch as the clothes in the various receptacles 75 usually will be in a different stage of the drying the drop in temperature due to evaporation of moisture is relatively low.

During the drying of the clothes considerable lint is carried into the air being circulated through the apparatus. If this lint is permitted to pass through the heater it acquires an objectionable odor which, when the heated lint is circulated through the drying chamber, imparts an objectionable odor to the clothes. In accordance with the present invention the inlets to the drying chambers are arranged so that the stream of air is diverted sharply before passing through the inlets and, consequently, the

lint tends to be thrown out and collect upon the bottom of the apparatus. Any lint which is not thus thrown out is trapped upon the screens 104, 105, 111 and 112 and is thus prevented from entering the drying chambers. When a certain amount of lint is thus collected upon the screens it will free itself by its own weight and drop to the bottom of the hot air chamber where it can be removed by opening the doors D. If the lint collected upon the screens fails to free itself, the valves 127 may be opened to cause compressed gas to be blown through the pipes 125 upon the screens and thus remove the lint. As an additional precaution against imparting an objectionable odor to the dry clothes by the heated lint, a deodorant is supplied from the tank 115 to the pan 120 which is located in the path of the circuit of heated air.

The action which effects the removal of the lint from the air stream is illustrated diagrammatically in Figs. 6, 7 and 8. As the air stream moves toward the drying chambers, its path is sharply diverted as indicated at K in Figs. 6, 7 and 8. In so doing the lint is thrown out by the action of centrifugal force and drops toward the bottom of the apparatus where it collects in a pile P. As the air stream passes through the screens, if any lint remains in the air stream some of it will be caught and collected upon the screens 104, 105, 111 and 112 as indicated at T in Figs. 7 and 8. If the collected lint is not removed from the screens by the force of the air stream itself, it can be removed periodically by compressed gas supplied from the pipes 125. When screens 104, 105, 111 and 112 are not used, the lint is removed solely by the action of centrifugal force as above described.

I claim:

1. In a laundry drier, in combination, a casing providing an air heating chamber communicating with a hot air chamber and a cool air chamber also provided by said casing below said heating chamber, means providing a drying compartment within said hot air chamber communicating with the cool air chamber, said drying compartment having an inlet from said hot air chamber positioned so as to cause a stream of air to travel downward partially around said drying compartment in said hot air chamber and then in a curved path before entering the drying compartment thereby tending to cast off lint, means for recirculating air through said chambers and compartment, and a screen disposed across said curved path.

2. In a laundry drier, in combination, a casing providing an air heating chamber communicating with a hot air chamber and a cool air chamber also provided by said casing below said heating chamber, means providing a drying compartment within said hot air chamber communicating with the cool air chamber, said drying compartment having an inlet from said hot air chamber positioned so as to cause a stream of air to travel downward partially around said drying compartment in said hot air chamber and then in a curved path before entering the drying compartment thereby tending to cast off lint, said casing having an opening providing communication between said compartment and the outside atmosphere, means for recirculating air through said chambers and compartment, and a screen disposed across said curved path.

3. In a laundry drier, in combination, a casing providing an air heating chamber communicating with a hot air chamber and a cool air chamber

also provided by said casing, means providing a drying compartment within said hot air chamber communicating with the cool air chamber and having an inlet from said hot air chamber positioned so as to cause a stream of air from said heating chamber to travel in a curved path before entering the drying compartment thereby tending to cast off lint, said casing having an opening providing communication between said compartment and the outside atmosphere, a perforated laundry receptacle mounted for rotation within said drying compartment and having an open end positioned adjacent said opening, said receptacle having an inwardly extending flange at its open end adapted to cooperate with said casing to provide a passage for hot air from said compartment into said receptacle through the open end thereof, and means for recirculating air through said chambers and compartment.

4. In a laundry drier, in combination, a casing providing an air heating chamber communicating with a hot air chamber and a cool air chamber also provided by said casing, means providing a drying compartment within said hot air chamber communicating with the cool air chamber and having an inlet from said hot air chamber positioned so as to cause a stream of air from said heating chamber to travel in a curved path before entering the drying compartment thereby tending to cast off lint, means for recirculating air through said chambers and compartment, and a screen extending across the path of travel of air from said hot air chamber into said compartment to collect lint not cast off from said air stream.

5. In a laundry drier, in combination, a casing providing an air heating chamber communicating with a hot air chamber and a cool air chamber also provided by said casing, means providing a drying compartment within said hot air chamber communicating with the cool air chamber and having an inlet from said hot air chamber positioned so as to cause a stream of air from said heating chamber to travel in a curved path before entering the drying compartment thereby tending to cast off lint, means for recirculating air through said chambers and compartment, a screen extending across the path of travel of air from said hot air chamber into said compartment to collect lint not cast off from said air stream, and means for removing lint collected upon said screen.

6. In a laundry drier, in combination, a casing, means to divide the casing into an air heating chamber, a hot air chamber and a cool air chamber, said hot air chamber and cool air chamber communicating with each other and each communicating with said heating chamber, means for heating air in the heating chamber, means providing a plurality of separate drying compartments within said hot air chamber each communicating with the cool air chamber and each including a perforated rotatable receptacle and having an inlet from said hot air chamber, said last mentioned means and said casing having a plurality of aligned normally uncovered openings providing communication between said compartments and the outside atmosphere and also providing annular passages around the openings in said casing from said hot air chamber to said compartments, means for recirculating air in a circuit through said chambers and compartments, a controllable exhaust for moisture laden air from said circuit, means for rotating said receptacles, and means associated with each

receptacle for stopping its rotation independently of the others.

7. In a laundry drier, in combination, a casing, means to divide the casing into an air heating chamber, a hot air chamber and a cool air chamber, said hot air chamber and cool air chamber communicating with each other and each communicating with said heating chamber, means for heating air in the heating chamber, means providing a plurality of separate drying compartments within said hot air chamber each communicating with the cool air chamber and each including a perforated rotatable receptacle and having an inlet at its lower part from said hot air chamber, said last mentioned means and said casing having a plurality of aligned normally uncovered openings providing communication between said compartments and the outside atmosphere and also providing annular passages around the openings in said casing from said hot air chamber to said compartments, means for recirculating air in a circuit through said chambers and compartments, a controllable exhaust for moisture laden air from said circuit, means for rotating said receptacles, and means associated with each receptacle for stopping its rotation independently of the others.

8. In a laundry drier, in combination, a casing, means to divide the casing into an air heating chamber, a hot air chamber and a cool air chamber, said hot air chamber and cool air chamber communicating with each other and each communicating with said heating chamber, means for heating air in the heating chamber, means providing a drying compartment within said hot air chamber communicating with the cool air chamber and having an inlet from said hot air chamber positioned so as to cause a stream of air from said heating chamber to travel in a curved path before entering the drying compartment thereby tending to cast off lint, said casing having a normally uncovered opening providing communication between said compartment and the outside atmosphere, a perforated laundry receptacle mounted for rotation within said drying compartment and having an open end of greater diameter than said opening and positioned adjacent the latter and spaced from said casing to provide a passage for hot air from said compartment into said receptacle through the open end thereof, means for rotating said receptacle, and means for recirculating air through said chambers and compartment.

FRED S. BOLTZ.
